J. C. CAPEHART.

LATH FOR WALL PLASTER FOUNDATIONS.

APPLICATION FILED APR. 23, 1917.

1,266,211.

Patented May 14, 1918.

Inventor:
John B. Capehart

Fig. A.

UNITED STATES PATENT OFFICE.

JOHN C. CAPEHART, OF FRANKFORT, KENTUCKY.

LATH FOR WALL-PLASTER FOUNDATIONS.

1,266,211.

Specification of Letters Patent. Patented May 14, 1918.

Application filed April 23, 1917. Serial No. 163,853.

To all whom it may concern:

Be it known that I, JOHN C. CAPEHART, a citizen of the United States, residing at Frankfort, in the county of Franklin and 5 State of Kentucky, have invented certain new and useful Improvements in Wood Laths for Wall-Plaster Foundations, of which the following is a specification.

My invention relates to a wall covering 10 for plaster providing a key base of such self-spaced uniform width as to receive and hold the plaster covering and to give a secure wall in the most economical way possible.

15 In the drawings accompanying this specification Figure 1 is a front elevation of wall in which my lath is used.

Fig. 2 is a rear elevation of the same.

Fig. 3 is a view of a lath itself.

20 Fig. 4 is a vertical transverse section through the wall shown in Fig. 1.

Fig. 1 is a front elevation of wall in which my lath is used, in which I show studding 5, self-spacing lath 6, intersected 25 by and assembled with plain uncut lath 7 partly covered with plaster 8 and illustrating the binding tape 9 glued to back of members.

Fig. 2 is a rear elevation of the same 30 showing in addition to above, plaster 10 appearing through key spaces occupying about $\frac{1}{3}$ of length of lath together with a better view of tape or connecting material 9.

Fig. 3 is a view of a lath itself as it 35 comes from the mill, made of waste lumber of like dimensions of common lath, usually $\frac{3}{8}$ of inch thick by $1\frac{1}{2}$ in. wide by 48 in. long, having saw cuts in its two edges of proper dimensions to form the key base, 40 each cut diagonally opposite the other so that no two spaces fall directly opposite on same lath.

Fig. 4 is a vertical transverse section through the wall shown in Fig. 1.

45 To describe the economy self-spacing lath in detail: It consists of a common wood lath with saw cuts in its two edges in dimensions about $\frac{1}{4}$ in. deep by $1\frac{3}{4}$ in. long diagonally opposite each other so as to form 50 a key base for plaster when assembled alter-

nately with plain uncut lath of like dimensions as shown in Figs. 1 and 2 accompanying this specification.

The economy self-spacing lath serves as follows:

First, to provide a simple economical device to overcome the slow, laborious and tedious process of tacking common wood laths singly on walls and ceilings properly spaced for plastering.

Second, to provide a device that will insure uniform spacing of wood laths automatically in order to procure a key base that will insure a perfectly fastened plaster in the most economical way possible.

Third, to reduce the unnecessary key base area to its real necessity, thereby saving two out of three pounds of plaster required to fill in common wood lath spaces and six to eight pounds out of every 10 pounds so required for some expensive modern devices.

Fourth, a further object is to enable one to place in position and tack more than one lath at a time on to the frame work of a building by fastening them together into 75 sections or units of the desired number of self-spacing laths assembled with plain uncut laths as indicated in Figs. 1 and 2.

Fifth, to enable unskilled labor or the plasterer himself in the absence of lather 80 to prepare a wall for plaster in the most economical way possible.

Having thus fully described my said invention, the economy self-spacing lath, what I claim as new and desire to secure by 85 Letters Patent is:

1. An article of manufacture, comprising a lath of ordinary standard dimensions having alternately in its opposite edges shallow recesses substantially the size of the cross 90 section of the lath and spaced apart substantially twice their length.

2. A lathing section consisting of a series of laths as set forth in claim 1, each in juxtaposition to and alternating with one of a 95 series of uncut laths, all of said laths being glued to and flexibly united by strips of tape so that said sections are capable of being rolled and unrolled.

JOHN C. CAPEHART.
